DETERGENT DISPENSER

Ernest H. Bucknell and Irving A. Ward, Los Angeles, Calif., assignors of five percent to the estate of Ralph E. Bletcher, deceased, three and one-third percent to James Hamilton Bletcher, trustee, ten percent to Pearl White Bletcher, ten percent to Hazel Skinner Brondum, eight percent to Charlotte Robertson, one percent to Kenneth Robertson, trustee, two and two-thirds percent to Gary B. Robertson, eight percent to James Hamilton Bletcher, two percent to Richard James Bletcher, eight percent to E. H. Bucknell, four and one-half percent to Myron Glauber, trustee, twelve and one-half percent to the estate of Mabel Bucknell, deceased, twenty and one-half percent to Marcia B. Liston, and four and one-half percent to Daniel G. Liston, trustee

Filed July 23, 1962, Ser. No. 211,708
12 Claims. (Cl. 137—604)

This invention relates to an improved detergent dispenser.

In many sinks a device is provided at the end of a flexible tubing through which either clear water or water mixed with a liquid detergent may be diverted to facilitate dishwashing. One of the problems involved in such structure is to provide satisfactory valving.

It is an object of this invention to provide such a device which is relatively resistant to initial opening but which once this original resistance is overcome, is relatively easy to open further and hold open.

Still a further object of this invention is to provide novel means for introducing detergent into the water stream flowing therethrough.

Other objects and advantages will be readily apparent from the following description:

In the drawings:

FIGURE 1 is a side elevation of a device embodying this invention.

FIGURE 2 is a side elevation in section.

FIGURE 3 is a fragmentary side elevation with parts thereof broken away.

FIGURE 4 is a fragmentary side elevation in section illustrating opening of the water flow valve.

FIGURE 5 is a view taken along line 5—5 of FIGURE 2.

FIGURE 6 is a view taken along line 6—6 of FIGURE 2.

FIGURE 7 is a perspective of the detergent reservoir seal.

FIGURE 8 is a fragmentary side elevation in section of the detergent valve in the closed position.

FIGURE 9 is a view similar to FIGURE 8 with the valve in the open position.

This invention is an improvement to the device described and claimed in prior United States Patent No. 2,795,460.

The device in general comprises a hollow shell or body 10 having a water inlet at one end 12 and an outlet at the opposite end 14. A lever 16 actuates the water control valve 18 to open or close off flow of water and a push button 20 actuates the detergent control valve 22 to admit detergent to water flowing through the structure.

At the inlet end 12 an internally threaded hose connector 24 is provided into which a male hose connector (not shown) on a water supply tube may be screwed. A sleeve 26 has one end thereof crimped as at 28 to secure

2

same to connector 24. The water control valve 18 which will be described in detail is housed within sleeve 26. Said sleeve has a tube 30 projecting through an opening 32 therethrough which tube is beaded as at 34 to prevent passage of same through opening 32.

The tube 30 is telescopically received within the reservoir sealing member 36 which has a tubular extension 38 projecting therefrom for this purpose. Telescopically received likewise within said extension 38 is a tube 40 having an externally threaded nipple 42 at the end thereof with a pair of projections 44 which abut against brush holder 46.

The brush holder has an outwardly turned flange which overlies shoulder 48 on brush base 50 in which bristles 52 are secured. A nozzle 54 having a central aperture 56 screws onto nipple 42. A rubber spray forming nozzle 58 fits over nozzle 54 having a series of fine holes 60 therein flow through which creates a spray.

Thus water flow is from connector 24 through valve 18 into tubing 30, tubular extension 38, tubing 40, nipple 42, aperture 56 in nozzle 54 and holes 60 in nozzle 58.

Turning now to water control valve 18, a valve housing 62 has a hollow tubular extension 64 which projects through washer 66, resilient washer 68 and bore 70 into connector 24. A spring 72 surrounds the extension 64 and abuts washer 66 and housing 62.

Positioned within housing 62 is a resilient valve member 74 which normally abuts the extremity of tubing 30 and blocks off water flow therethrough. The valve member is mounted in housing 62 by a spider 76 the legs of which abut internal shoulder 78 of the housing.

A cup shaped valve retainer 80 slidably fits on tubing 30 and abuts spider 76. A resilient washer 82 is positioned between retainer 80 and rigid washer 84 which in turn abuts inturned flange 86 on housing 62 securing the valve member 74 in the housing.

Lever 16 at its foremost extremity has a slot 88 which receives projection 90 on liner retainer 92. The lever also has a pair of hooks 94 which engage inturned flanges 96 on sleeve 26 which sleeve has the lower forwardmost portion thereof cut away as at 98 to receive the pivoting lever.

Extending between hooks 94 is a toggle 100. The toggle has an upwardly faced U-shaped section 102, which receives tube 30, and a pair of downwardly turned legs 104 terminating in outwardly projecting ends 106 which project through holes 108 in hooks 94.

As seen in FIGURES 2 and 3 when the trigger or lever 16 is released, spring 72 urges control valve 18 to the right against toggle 100 until valve member 74 abuts the end of tube 30. When the handle or body 10 is grasped and lever 16 depressed the spring 72 resists movement of valve 18 which spring can be of sufficient resistance to avoid accidental or too rapid opening resulting in an unwanted spray of water.

After the initial reluctance of the spring is overcome and as toggle 100 is further pivoted counter-clockwise in FIGURES 2 and 3 by further depression of lever 16 the mechanical advantage increases so that further opening of the valve requires less force.

When the valve 18 has traveled to its fully open position as seen in FIGURE 4, the toggle 100 and specifically legs 102 have assumed almost a straight line relationship with spring 72 reducing the force necessary to apply to lever 16 to hold the valve fully open. When the lever

16 is released, spring 72 pivots same to the initial or open position with valve member 74 again abutting tube 30.

In this embodiment, liquid detergent is stored in a reservoir between body 10 and tube 30 and same is designated 110. This reservoir is closed at one end by nozzle 54, brush holder 46 and packing 112 in conjunction with nipple 42 and at the other end by sealing member 36. The member 36 is formed of a circular flange 114 having a series of parts 116 punched therethrough to which flange extension 38 heretofore described is connected. An opposed similar circular flange 118 is provided having a tubular extension 120 thereon which extension surrounds tubing 30 and is spaced therefrom. A resilient liner 122 is provided within extension 120 which surrounds same. The outermost portion of extension 120 is necked inwardly to clamp one extremity of liner to tubing 30. The remaining end of liner 122 projects between flanges 114 and 118 and is beaded to form a seal for the reservoir. Tube 30 and extension 120 each has a hole 124 and 126 therein which latter hole contains a ball 127. A leaf spring member 128 has a central bore through which tube 30 passes and an upper arm 130 which bears against the upper surface of extension 120 and a lower arm 132 which bears against ball 128 urging same to push a portion of liner 122 into hole 124 to prevent flow of detergent into tube 30.

Button 20 has a pair of legs such as 134 depending therefrom which straddle tube 30 and extension 120 and is notched as at 136 to fit into complementary notches in arm 132. When the button 20 is depressed the arm 132 is likewise depressed through legs 134 releasing the spring pressure on ball 127 which then permits the liquid detergent to be drawn from the reservoir into the stream of water flowing through tube 30 until button 20 is released and ball 127 is again seated in hole 124.

It is to be noted that the lever 16 and button 20 are positioned on opposite sides of body 10 and in sufficient proximity to permit them to be operated by one hand of the user.

While what hereinbefore has been described is the preferred embodiment of this invention, it is readily apparent that alterations and modifications can be resorted to without departing from the scope of this invention.

We claim:

1. In a detergent disperser of the type connected to a water supply by a flexible hose and a hollow body having an inlet connectible to said hose at one extremity and an outlet at the other extremity, the combination therewith of a tubing within said body, valve means in said body controlling flow through said tubing, a seal in said body forming a detergent reservoir therein, a hole in said tube, a resilient liner surrounding said tube and spaced therefrom, a ball, means urging said ball into said liner and said liner into said hole shutting off flow from said reservoir to said tube whereby flow through said tube draws detergent from said reservoir when said liner is not in said hole.

2. In a detergent disperser of the type connected to a water supply by a flexible hose and a hollow body having an inlet connectible to said hose at one extremity and an outlet at the other extremity, the combination therewith of a tubing within said body, valve means in said body controlling flow through said tubing, a seal in said body forming a detergent reservoir therein, a hole in said tube, a resilient liner surrounding said tube and spaced therefrom, a ball, means urging said ball into said liner and said liner into said hole shutting off flow from said reservoir to said tube, said last mentioned means including a spring urging said ball, a push button external of said body and connected to said last mentioned spring to release said ball when the button is depressed whereby flow through said tube and said valve means draws detergent through said hole when said ball is released.

3. In a detergent disperser of the type connected to a

water supply by a flexible hose and a hollow body having an inlet connectible to said hose at one extremity and an outlet at the other extremity, the combination therewith of a tubing within said body extending from adjacent said outlet to a position short of said inlet, valve means movable longitudinally in said body to abut the end of said tubing nearest said inlet, spring means urging said valve into the tube abutting position, lever means, a toggle connection between said lever connection and said valve means whereby movement of said lever moves said toggle to move said valve means out of abutment with said tube against said spring means, a seal in said body forming a detergent reservoir therein, a hole in said tube, a resilient liner surrounding said tube and spaced therefrom, a ball, means urging said ball into said liner and said liner into said hole shutting off flow from said reservoir to said tube whereby flow through said tube draws detergent from said reservoir when said liner is not in said hole.

4. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, valve means movable longitudinally in said body to abut the end of said tubing nearest said inlet, spring means urging said valve into the tube abutting position, lever means, a toggle connection between said lever connection and said valve means whereby movement of said lever moves said toggle to move said valve means out of abutment with said tube against said spring means, a seal in said body forming a detergent reservoir therein, a hole in said tube, a resilient liner surrounding said tube and spaced therefrom, a ball, means urging said ball into said liner and said liner into said hole shutting off flow from said reservoir to said tube, said last mentioned means including a spring urging said ball, a push button external of said body and connected to said last mentioned spring to release said ball when the button is depressed whereby flow through said tube and said valve means draws detergent through said hole when said ball is released.

5. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, valve means movable longitudinally in said body to abut the end of said tubing nearest said inlet, spring means urging said valve into the tube abutting position, lever means, a toggle connection between said lever connection and said valve means whereby movement of said lever moves said toggle to move said valve means out of abutment with said tube against said spring means, said toggle means being formed to increase the mechanical advantage as said lever is moved, a seal in said body forming a detergent reservoir therein, a hole in said tube, a resilient liner surrounding said tube and spaced therefrom, a ball, means urging said ball into said liner and said liner into said hole shutting off flow from said reservoir to said tube whereby flow through said tube draws detergent from said reservoir when said liner is not in said hole.

6. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, valve means movable longitudinally in said body to abut the end of said tubing nearest said inlet, spring means urging said valve into the tube abutting position, lever means, a toggle connection between said lever connection and said valve means whereby movement of said lever moves said toggle to move said valve means out of abutment

with said tube against spring means, said toggle means being formed to increase the mechanical advantage as said lever is moved, a seal in said body forming a detergent reservoir therein, a hole in said tube, a resilient liner surrounding said tube and spaced therefrom, a ball, means urging said ball into said liner and said liner into said hole shutting off flow from said reservoir to said tube, said last mentioned means including a spring urging said ball, a push button external of said body and connected to said last mentioned spring to release said ball when the button is depressed whereby flow through said tube and said valve means draws detergent through said hole when said ball is released.

7. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever.

8. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever, said toggle having a U-shaped portion bearing against said tube and a pair of downwardly turned legs connected to said lever.

9. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever, a seal in said body forming a detergent reservoir therein, a hole in said tube, a resilient liner surrounding said tube and spaced therefrom, a ball, means urging said ball into said liner and said liner into said hole shutting off flow from said reservoir to said tube whereby flow through said tube draws detergent from said reservoir when said liner is not in said hole.

10. In a detergent disperser of the type connected to a water supply by a flexible hose and a hollow body having an inlet connectible to said hose at one extremity and an outlet at the other extremity, the combination

therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever, a seal in said body forming a detergent reservoir therein, a hole in said tube, a resilient liner surrounding said tube and spaced therefrom, a ball, means urging said ball into said liner and said liner into said hole shutting off flow from said reservoir to said tube, said last mentioned means including a spring urging said ball, a push button external of said body and connected to said last mentioned spring to release said ball when the button is depressed whereby

15 11. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever, said toggle having a U-shaped portion bearing against said tube and a pair of downwardly turned legs connected to said lever, a seal in said body forming a detergent reservoir therein, a hole in said tube, a resilient liner surrounding said tube and spaced therefrom, a ball, means urging said ball into said liner and said liner into said hole shutting off flow from said reservoir to said tube whereby flow through said tube draws detergent from said reservoir when said liner is not in said hole.

20 12. In a detergent disperser of the type connected to a water supply by a flexible hose and a hollow body having an inlet connectible to said hose at one extremity and an outlet at the other extremity, the combination therewith of a tubing within said body extending from adjacent said outlet to a position short of said inlet, a resilient valve member adapted to abut the extremity of said tube adjacent said inlet, a valve member carrier in communication with said inlet, spring means surrounding said carrier and seated against an obstruction in said body urging said carrier and hence said valve member into position wherein the latter shuts off flow through said carrier to said tube, a lever pivotally mounted within said body, a toggle pivotally connected to said lever bearing against said carrier and moving said carrier against the urging of said spring upon depression of said lever, said toggle having a U-shaped portion bearing against said tube and a pair of downwardly turned legs connected to said lever, a seal in said body forming a detergent reservoir therein, a hole in said tube, a resilient liner surrounding said tube and spaced therefrom, a ball, means urging said ball into said liner and said liner into said hole shutting off flow from said reservoir to said tube, said last mentioned means including a spring urging said ball, a push button external of said body and connected to said last mentioned spring to release said ball when the button is depressed whereby

flow through said tube and said valve means draws detergent through said hole when said ball is released.
